(57) **CLAIM**

The ornamental design for an wall or door mountable holder, as shown and described.

DESCRIPTION

FIG. 1 is a right side exploded view of a wall or door mountable holder embodying the new design;

FIG. 2 is a right side partially assembled view;

FIG. 3 is a right side assembled view;

FIG. 4 is a right, top, front, perspective view; and,

FIG. 5 is a left, rear, top perspective view.

The opposite side of each figure is a mirror image of that figure.

The broken line representations of the mounting receptacle and screw are for purposes of illustration, and form no part of the claimed design.
